UNITED STATES PATENT OFFICE.

CARL J. NILSSON, OF CAMBRIDGE, MASSACHUSETTS.

ICE-CREAM CABINET.

1,424,373.

Specification of Letters Patent. Patented Aug. 1, 1922.

Application filed June 24, 1921. Serial No. 420,197.

To all whom it may concern:

Be it known that I, CARL J. NILSSON, a citizen of the United States of America, and resident of Cambridge, in the county of 5 Middlesex and State of Massachusetts, have invented new and useful Improvements in Ice-Cream Cabinets, of which the following is a specification.

This invention relates to icecream cabinets 10 and more particularly to means for opening the covers for icecream containers of such cabinets.

At soda fountains and other places where icecream is dispensed in large quantities and 15 where the attendants must work rapidly, especially during rush hours, considerable difficulty is experienced in the manipulation of the aforesaid covers. The usual method is to have a cover which seats in an opening 20 in the top of the chest containing the icecream containers and the surrounding ice, these covers being lifted by hand. The attendant's hands are usually fully occupied with the icecream dipper and with the glass 25 or cup so that it is awkward to lift the covers by hand; moreover, the space is usually quite limited and it is a cause of annoyance and delay to find a vacant spot upon which to rest the cover while the icecream is being 30 dipped from the container when the cover is not hinged but detachable. The practical result of this inconvenience and annoyance is that the covers are usually left off the containers, or if hinged to the chest they are 35 left open, thus giving rise to unsanitary conditions and the rapid softening of the icecream.

The objects of the present invention are to provide an icecream cabinet which has 40 mechanism for opening the covers by means of foot pedals, which has the foot pedals conveniently located, which has the connecting mechanism located in such manner as not to be unsightly and not to obstruct the 45 operations of the attendant, and which is simple and inexpensive to manufacture.

In order more clearly to set forth the nature of the invention, I have shown one concrete embodiment in the accompanying 50 drawings, in which:

Fig. 1 is a plan view of an icecream cabinet embodying the invention;

Fig. 2 is a vertical transverse section on line 2—2 of Fig. 1; and

Fig. 3 is a front detail elevation of one of 55 the foot pedals.

The particular embodiment of the invention shown for the purpose of illustration comprises a chest having side walls 1, 2, 3 and 4, a bottom 5, corner posts 6, 7, 8 and 60 9 intermediate front posts 10, intermediate rear posts 11, a top formed in two interfitting parts 12 and 13 and covers 14 hinged to the top part 13.

According to the present invention the 65 covers are provided with upstanding lugs 15 and operating pedals 16 are pivoted at the lower forward corner of the chest intermediate the ends thereof, the pedals and lugs 15 being connected together by means 70 of a chain 17 running over pulleys 18 and 19. The chain 17 extends along the bottom of the chest at a level above the depending portions 20 (Fig. 2) of the side walls so as to be out of sight so as not to interfere with 75 mopping beneath the chest. At the rear of the chest the chain extends vertically through channel members which are built into the chest in the form of the aforesaid rear intermediate posts. The portion 12 of 80 the top of the chest is recessed at 21 to facilitate the application and removal of the chain 17. Springs 22 are preferably associated with the lugs 15 to give the covers an initial closing impulse when the foot 85 pedal is released, thereby to throw the covers past vertical position so that they will continue to close by gravity.

As shown in the drawings the foot pedals are preferably mounted in slots 23 in the 90 forward intermediate posts 10 upon a single rod 24 extending the full length of the cabinet.

I claim:

1. An icecream cabinet comprising a chest 95 having an opening for an icecream container in the top thereof in spaced relation to the sides thereof, a cover for said opening, and means for opening said cover including a pedal at the front of the chest and a connection extending from the pedal to the cover along two sides of the chest, said connection being entirely within the outlines of the chest so as not to interfere with cleaning around and beneath the chest. 100

2. An icecream cabinet comprising a chest having an opening for an icecream container in the top thereof, a cover for said opening, 105

and means for opening said cover including a pedal at the lower forward corner of the chest intermediate the ends thereof, a connection extending from the pedal to the cover, and guide means including a channel member for said connection.

3. An icecream cabinet comprising a chest having an opening for an icecream container in the top thereof, a cover for said opening, and means for opening said cover including a pedal at the lower forward corner of the chest intermediate the ends thereof, and a connection extending rearwardly along the bottom of the chest, thence upwardly through a channel member built in the chest, and thence to the cover.

4. An icecream cabinet comprising a chest having a plurality of openings for icecream containers in the top thereof, covers for said openings, means for opening said covers including pedals at the lower forward corner of the chest intermediate the ends thereof and connections between the pedals and covers respectively, and a common support for said pedals.

5. An icecream cabinet comprising a chest having a plurality of openings for icecream containers in the top thereof, covers for said openings, means for opening said covers including pedals at the lower forward corner of the chest intermediate the ends thereof and connections between the pedals and

covers respectively, and a rod extending along said corner for supporting all of said pedals.

35

6. An icecream cabinet comprising a chest having a plurality of openings for icecream containers in the top thereof, covers for said openings, supporting posts at the front of said chests having slots therein, means for opening said covers including pedals in said slots, and a rod extending through said slots for pivotally supporting said pedals.

7. An icecream cabinet comprising a chest having an opening for an icecream container in the top thereof, a cover for said opening, a supporting post at the front of the chest having a slot therein, and means for opening said cover including a pedal in said slot and a connection between the pedal and the cover.

8. An icecream cabinet comprising a chest having a plurality of openings for icecream containers in the top thereof, covers for the openings, supporting posts at the front of said chest having slots therein, means for opening said covers including pedals in said slots, and connections from said pedals to the covers corresponding thereto, said connections extending through channel members in said chest.

Signed by me at Boston, Massachusetts,
this 20th day of June 1921.

CARL J. NILSSON.
